[57] ABSTRACT

Apparatus that includes a rotary drum having its axis extending substantially horizontally and perpendicular to the longitudinal axis of the coke oven battery is positioned adjacent to the discharge end of a coke oven chamber to receive coke pushed from the chamber through a coke guide. The rotary drum is supported on rollers and is arranged to rotate as the coke is introduced into the drum to displace coke from the bottom quadrant of the drum chamber and provide space for receiving additional quantities of coke from the same coke oven chamber. The inner wall of the rotatable drum has pocket type lifter devices thereon to convey the coke upwardly in the chambers and also to discharge the coke into a chute that extends outwardly from the drum chamber. The drum is rotatably supported in a housing that has air cleaning devices thereon to remove the dust generated during the coke discharging operation. A water spray device is positioned within the drum to quench the coke as it is discharged from the coke oven.

APPARATUS FOR RECEIVING COKE PUSHED FROM HORIZONTAL COKE OVENS

BACKGROUND OF THE INVENTION

1. Field of the Invention

This invention relates to apparatus for receiving coke pushed from a horizontal coke oven and more particularly to a rotary drum receiver positioned perpendicular to the coke oven battery.

2. Description of the Prior Art

U.S. Pat. No. 3,367,844 discloses a rotary drum type receiver for coke discharged from horizontal coke ovens. The rotary drum is positioned parallel to the coke oven battery and has spraying devices thereon to quench the coke.

Co-pending application, Ser. No. 187,404, entitled "Material Transfer Apparatus For A Rotary Drum," filed Oct. 7, 1971, discloses dust collecting apparatus positioned adjacent the discharge end of the drum. In both U.S. Pat. No. 3,367,844 and the above co-pending application the coke is discharged from the drum onto an endless conveyor. The drum type receivers have in the past been employed as quenching devices and there is a need for a drum type receiver that is arranged to receive the coke from the coke oven chamber and to displace at least a portion of the coke from the lower quadrant of the drum receiver chamber while additional coke is introduced into the drum receiver chamber. Further, there is a need for a drum type hot coke receiver that receives coke from a coke oven chamber without discharging dust into the atmosphere.

SUMMARY OF THE INVENTION

The present invention is directed primarily to improvements in receivers for hot coke that is being pushed from a horizontal coke oven chamber and includes a drum type receiver mounted on a movable support member. The drum type receiver is arranged to be pushed adjacent the coke discharge end of the coke oven chambers with the axis of the drum extending substantially horizontally and perpendicular to the coke oven battery. The drum receiver has a chamber rotatable about the drum axis with a central opening for introducing coke into the drum receiver chamber from the coke oven and an outlet opening to discharge the coke from the drum receiver chamber. A coke oven guide connects the outlet opening of the coke oven chamber with the central inlet opening of the drum receiver and the coke discharged through the coke oven guide is deposited in the lower quadrant of the drum receiver chamber. During the pushing operation the drum receiver is rotated about its axis to displace at least a portion of the coke in the lower quadrant of the drum receiver chamber to provide space for additional coke discharged from the coke oven.

A housing encloses the drum receiver and has an open upper end portion. Filter members close the housing open end portion and suitable suction means are provided to collect the dust formed in the receiver chamber in the filter means. The drum receiver has a plurality of annular ring members which are supported on roller members which, in turn, are supported on the movable support member. Certain of the rollers are driven to rotate the drum receiver and displace the coke within the lower quadrant of the drum receiver chamber. Other rollers are provided to abut the side

walls of one of the ring members to maintain the drum receiver on the support member and permit longitudinal expansion and contraction of the drum member.

The housing enclosing the drum receiver has a side opening with parallel rail members supported thereby. The coke guide is supported on the rail members and is movable into the central opening of the drum receiver when not in use.

BRIEF DESCRIPTION OF THE DRAWINGS

FIG. 1 is a view of the coke receiving apparatus in elevation and partially in section.

FIG. 2 is a view of the coke receiving apparatus taken parallel to the longitudinal axis of the coke oven battery, illustrating a coke guide device between the outlet opening of a coke oven chamber and the inlet opening of the coke receiving apparatus.

FIG. 3 is a top plan view of the coke receiving apparatus, illustrating the dust filters and suction fans.

DESCRIPTION OF THE PREFERRED EMBODIMENT

Referring to the drawings and particularly to FIG. 2 there is illustrated a coke oven battery generally designated by the numeral 10 that includes a plurality of transversely extending coke oven chambers 12. The coke oven battery has a coke discharge side 14 in which the coke oven chambers 12 have coke discharge openings 16. The coke formed in the coke oven chambers 12 is discharged through the discharge opening 16 into coke receiving apparatus which is generally designated by the numeral 18. Between the coke receiving apparatus 18 and the coke oven battery discharge side 14 is a conventional coke guide 20 that is supported on a coke guide car 22. The coke guide 20 is arranged to conduct the coke discharged from the coke oven chamber 12 to the coke receiving apparatus 18.

Referring to FIGS. 1 and 2 the coke receiving apparatus 18 includes a rotary drum receiver 24 that has an axis 26 illustrated by the —— line in FIG. 2. The drum receiver 24 has a generally annular configuration with a pair of spaced annular side plates 28 and polygonal end plates 30 that provide a generally U-shaped cross section for the drum receiver 24. The annular side plates 28 have a central opening 32 through which the coke is discharged from the coke guide 20 into the chamber of the drum receiver 24.

The drum receiver 24 is mounted on a movable support member 34 that is, in turn, mounted on wheels 36. Rails 38 extend parallel to and along the coke discharge side 14 of coke oven battery 10 and the movable support member 34 is arranged to move on the rails 38 to position the coke receiving apparatus 18 opposite a selected coke oven chamber 12. Pairs of rollers 40 are mounted on supports 42 which extend upwardly from the support member 34.

The drum receiver 24 has a pair of ring like tires or bearing surfaces 44 secured to the outer wall 30 and are supported on the rollers 40. In this manner the drum receiver 24 is rotatably supported on rollers 40. Suitable drive means such as a diesel engine or the like (not shown) are connected to certain of the rollers 40 and arranged to rotate the rollers 40 which, in turn, rotate the drum receiver 24 about the axis 26. As illustrated in FIG. 2, a pair of rollers 46 are suitably mounted with their axes 48 substantially vertical and the lower surfaces abut the side walls of the bearing

member 44. With this arrangement, the rollers 46 maintain the rotatable drum receiver on the movable support member 34 and permit expansion and contraction of the metallic drum receiver 24.

Housing 50 forms an enclosure around the drum member receiver 24 and has an open top portion 52. A suitable filter, such as a gravel or fiber filter, 54 (FIG. 1) extends across the opening 52 and suitable fans 56 are positioned in the opening 52 and are arranged to draw the dust and vapors within the enclosure 50 upwardly through the enclosure 50 and deposit the dust in the filter 54. With this arrangement, the dust created by transferring the coke from the coke oven chamber through the coke guide 20 into the chamber of the rotary receiving drum 24 is collected on the filter and not discharged to the atmosphere.

The housing 50 has a central opening 58 with a suitable enclosure or cover thereon and a pair of rails 60 are secured to the housing 50 and extend into the opening 32 of the drum receiver 24. The coke oven guide 20 has rollers 62 which are positioned on the rails 60. With this arrangement, the coke guide 20 can be moved away from the coke oven chamber 12 within the rotary receiver drum 24 so that the coke guide 20 can be transported with the coke receiving apparatus 18 as it is moved from one coke oven chamber to another. When the coke guide 20 is moved into operative position abutting the opening 16 of a coke oven chamber it is preferred that the coke guide 20 be supported by coke guide car 22 on roller 64.

Pocket type lifter devices 66 are secured to the inner surface of the drum receiver wall 30 and are arranged upon rotation of the drum to displace coke within the lower quadrant of the drum receiver chamber and move the coke upwardly therein. A chute 68 has a top opening 70 that opens into the chamber of the drum 24 and has a movable lid 72. When the lid is in the open position as indicated in solid lines in FIG. 1 rotation of the drum 24 will convey coke particles by means of the pocket lifters 66 to the upper quadrant of the chamber and discharge the coke onto a plate 25 and the coke will then slide the plate 25 through the opening 70 into chute 68. When the gate 72 is closed the coke will not pass through the opening 70.

The housing 50 has a hopper like bottom portion 74 which is arranged to receive the coke that occasionally spills over from the drum 24 and a suitable collecting means (not shown) may be employed to periodically remove the coke within hopper portion 74.

A coke quenching spray 76 is connected by means of a conduit 78 to a source of water 80 to provide a water quenching spray within the lower quadrant of the drum receiver 24.

The above described apparatus is arranged to receive hot coke discharged from the coke oven chamber 12 in the following manner. The coke guide 20 is retracted through the opening 58 in housing 50 within the opening 52 of the drum receiver 24. The movable support member 34 is transported along the rails 38 to a position where the axis 26 of the drum receiver 24 is aligned with the axis of the coke oven chamber to be pushed. The coke guide 20 is moved outwardly from the housing 50 to the position illustrated in FIG. 2 where the coke oven guide is supported on the roller 64 and encloses the opening 16 in the coke oven chamber 12. The coke is then pushed from the coke oven chamber 12 through the guide 20 into the opening 32 of the

rotary drum receiver 24. The coke flows by gravity in the lower quadrant of the drum receiver chamber 24 and the drum 24 is rotated at a preselected peripheral speed by the driven rollers 40. The rotation of the drum 24 displaces at least a portion of the coke in the lower quadrant of the drum receiver chamber to provide room for coke subsequently pushed from the same chamber. During the pushing operation the suction fans 56 and the quenching spray 76 are energized. The water spray 76 quenches the coke and the suction fans 56 withdraw the vapors and dust through the filter 54 where the dust particles are collected and not discharged to the atmosphere. When it is desired to discharge the coke from the receiver 18 onto a coke wharf 82 the lid is opened and the drum receiver 24 is rotated. The coke in the lower portion of the drum receiver 24 is picked up by the pocket devices 66 and deposited either on the inclined plate 25 or directly in the opening 70 of chute 68. The coke thus deposited on the inclined plate and the coke entering opening 70 is discharged through the outlet opening 84 of chute 68 onto the coke wharf 82.

According to the provisions of the patent statutes, I have explained the principle, preferred construction and mode of operation of my invention and have illustrated and described what I now consider to represent its best embodiments. However, I desire to have it understood that, within the scope of the appended claims, the invention may be practiced otherwise than as specifically illustrated and described.

I claim:

1. Apparatus for receiving hot coke being pushed from a horizontal coke oven chamber of a coke oven battery comprising,

a drum receiver mounted on a movable support member, said drum receiver arranged to be positioned adjacent the coke discharge end of the coke oven chambers,

said drum receiver positioned on said support member in a manner that the axis of said drum receiver extends substantially horizontally and perpendicular to said coke oven battery,

said drum receiver having a chamber rotatable about said drum axis, a central inlet opening for introducing coke into said drum receiver chamber and an outlet opening to discharge coke from said drum receiver chamber,

said central coke inlet opening positioned adjacent to the discharge opening of said coke oven chamber,

means to introduce coke discharged from said coke oven chamber into said drum receiver central opening,

means to rotate said drum to displace within said chamber at least a portion of the coke in the lower quadrant of said drum receiver chamber,

a housing enclosing said drum receiver, said housing having a top opening,

filter means positioned in and closing said top opening, and

suction means positioned above said filter means to collect the dust formed in said drum receiver chamber in said filter means.

2. The apparatus of claim 1 in which said drum receiver includes,

a pair of spaced annular side walls connected to a generally annular end wall so that said drum re-

ceiver has a generally U-shaped configuration in cross-section.

3. The apparatus of claim 2 which includes carrier pockets secured to the inner surface of said end wall, said pockets arranged upon rotation to displace coke 5 upwardly in said chamber from the lower quadrant of said chamber.

4. The apparatus of claim 1 in which said drum receiver chamber has an annular configuration with a central circular opening having a diameter sufficient to 10 receive a coke oven guide member.

5. The apparatus of claim 1 which includes annular ring members secured to the outer wall of said drum receiver,

a plurality of roller members rotatably supported on 15 said movable support member,

said drum receiver supported on said rollers with said annular ring members rotatably supported on said rollers,

means to rotate certain of said rollers to thereby rotate 20 said drum receiver.

6. The apparatus of claim 5 which includes, pairs of other rollers abutting the side walls of one of said ring members,

said pairs of other rollers operable to maintain said drum receiver on said support member and permit longitudinal expansion and contraction of said drum member.

7. The apparatus of claim 4 which includes, a housing surrounding said drum receiver and having a side opening, rail members supported by said housing and extending through said side opening into said drum receiver central opening, a coke guide having rollers mounted on said rail members, said coke guide arranged to move axially into said drum receiver and outwardly into operative relation with said coke oven chamber discharge opening.

8. The apparatus of claim 1 which includes, a discharge chute extending through said drum receiver chamber outlet opening and into said chamber, said discharge chute operable to convey coke from said drum receiver chamber upon rotation of said drum receiver.
